ATTORNEY

UNITED STATES PATENT OFFICE.

CHARLES GREEN, OF MUSCATINE, IOWA, ASSIGNOR OF ONE-FOURTH TO EVERET F. RICHMAN AND ONE-FOURTH TO CHARLES J. RICHMAN, BOTH OF MUSCATINE, IOWA.

HAMMER.

Application filed June 6, 1921. Serial No. 475,523.

To all whom it may concern:

Be it known that I, CHARLES GREEN, a citizen of the United States, residing at Muscatine, in the county of Muscatine and 5 State of Iowa, have invented new and useful Improvements in Hammers, of which the following is a specification.

This invention relates to power hammers and has for its object the provision of a 10 novel and efficient power hammer which is provided with means controllable by the operator whereby the length of stroke and consequently the power of the blow may be regulated to suit different conditions at the 15 will of the operator even while the device is in full operation.

An important object is the provision of a device of this character which is also provided with means readily operable by the 20 user whereby the device may be thrown into and out of operation in a very simple and efficient manner.

Another object is the provision of a device of this character which is provided 25 with cushioning means whereby the shock of the operation of the lever carrying the hammer may be effectively cushioned or absorbed.

A further object is the provision of a 30 device of this character which is so constructed as to involve the use of merely a small number of parts, the fewness of the parts together with their peculiar construction rendering the device readily repairable 35 in the case of derangement.

An additional object is the provision of a device of this character which will be simple and inexpensive in manufacture, highly efficient in use, durable in service and 40 a general improvement in the art.

With the above and other objects and advantages in view, the invention consists in the details of construction to be hereinafter more fully described and claimed, and illustrated in the accompanying drawings in 45 which,

Figure 1 is a side elevation of the device.

Figure 2 is a front elevation.

Figure 3 is a plan view of the hammer 50 end of the operating lever.

Figure 4 is a horizontal sectional view taken on a plane considerably below the operating lever.

Figure 5 is a vertical cross-sectional view

taken through the pivotal connection of the 55 lever with its support.

Figure 6 is a vertical sectional view taken through the drive shaft, and

Figure 7 is a detail horizontal section 60 through the operating rod taken immediately above the rocking lever.

Referring more particularly to the drawings I have shown my device as comprising a suitable base 10 from one end of which rises a vertical upright 11 and from the intermediate portion of which rises an upright 12. Secured upon the upper end of the upright 11 is an anvil member 13 and also secured upon the rear base of the upright 11 is a vertically extending guide 14 65 formed at its intermediate portion with an elongated slot 15 and having secured to its upper end portion a pair of forwardly extending space guide yokes 16. Slidable through these yokes 16 is a vertically movable bar 17 carrying a hammer head 18 disposed above and cooperating with the anvil 13. 70

Secured upon the upper end of the upright support 12 is a bearing member 19 80 which is pivotally connected as shown at 20 with a bearing member 21 secured to the intermediate portion of an operating lever 22. The forward end of this lever 22 is bifurcated for straddling engagement upon 85 the bar 17 and is formed with slots 23 through which passes a pin 24 extending transversely through the bar 17 whereby to constitute an operative connection between this operating lever and the hammer bar. 90 The rear end of the lever 22 is bifurcated as shown and is formed with slots 25 for a purpose to be described.

It is not an essential feature of the invention but it is well to mention in passing that 95 I prefer to employ braces 26 connected with the upper end of the upright 12 and with the upper end of the guide 14. I also provide braces 27 connected with the lower portion of the guide 14 and with the lower 100 one of the yoke 16 whereby to provide strength. In actual practice it may likewise be found advisable to provide braces 28 connected with the lower portion of the upright 11 and with the upper portion of 105 the upright 12 whereby to hold these members relatively rigid.

Secured upon the base 10 rearwardly of

the upright 12 are bearings 29 through which is journaled a shaft 30 provided at one end with a balance wheel 31 and provided at its other end with a pulley 32 about 5 which is trained a belt 33 driven by any suitable power device, not shown.

Secured upon the intermediate portion of the shaft 30 is an eccentric 34 encircled by an eccentric strap 35 which is connected with 10 the lower end of a vertically reciprocating rod 36 which is slideable through a block 37 disposed within the bifurcation at the rear end of the lever 22. This block 37 carries oppositely extending trunnions 38 which 15 pass through the slot 25 as shown. Disposed upon the rod 36 is a coil spring 39 which has its lower end abutting against the block 37 and which has its upper end abutting against a nut 40 threaded onto 20 the upper extremity of the rod 36. Also encircling the rod 36 is a coil spring 41 which has its upper end abutting against the under side of the block 37 and which has its lower end abutting against a stop-collar 42 25 secured upon the rod 36. By this construction it will be seen that when the shaft 30 is rotated the rod 36 will be reciprocated vertically and this will result in swinging the lever 32 to bring the hammer member 18 30 carried thereby into engagement with the anvil 13 or into engagement with work disposed upon the anvil. It is to be noted that the springs 39 and 41 cushion the shock and avoid breaking the parts when the machine 35 is in operation. It is also to be observed that by adjusting the nut 40 the degree of tension of the springs may be regulated to meet varying conditions.

In order that the machine may be readily 40 controlled, that is thrown into or out of gear as may be desired, I provide a yoke 43 pivoted upon the base 10 at the rear of the shaft 30 and carrying a roller 44 which engages against the rear side of the rear stretch of 45 the belt 33. Pivoted upon the forward portion of the base 10 is a treadle member 45 which is angular in shape and which has the free end of its rearmost arms connected with the upper portion of the yoke 43 by means of 50 suitable links 46. It will be seen that when the operator presses upon the treadle 45 and effects rocking of the treadle the links 46 will pull upon the yoke 43 and move the roller 44 into close engagement with the rear 55 stretch of the belt so that the belt will grip the pulley 32 with a sufficient degree of friction to insure rotation of the shaft 30 for driving the machine.

In order that the degree of movement of 60 the lever 22 may be regulated, I provide a link 47 slideable along one side of the rear end of the lever 22 and pivotally connected with the projecting end of one of the trunnions 38. Secured upon the rear side of 65 the upright 12 is a supporting bracket

upon which is pivoted a lever 49 which has its upper end pivotally and slidably connected with the forward end of the link 47 and which has its lower end pivotally connected with a link 50 which is in turn pivotally connected with a lever 51 having a grip actuated pawl mechanism 52 cooperating with a notch segment 53 secured at the forward end of the base 10.

In the operation of the device it will be 75 seen that when the operator presses upon the treadle 45 the yoke 43 will be moved forwardly to bring the roller 44 thereof against the rear stretch of the belt 33 so that the shaft 30 will be operated. When this shaft 30 rotates, the eccentric 34 carried thereby will effect vertical reciprocating movement of the rod 36 and this will of course cause the rocking movement of the lever 22 so that the hammer member 18 thereof will operate with the anvil for producing a hammering action upon any work disposed upon the anvil. As stated above the provision of the springs 39 and 41 is important as it provides the proper cushioning effects so as to 80 take up the shock or jar and to permit a certain amount of lost motion at the rear of the lever to avoid breaking any of the parts. Whenever it is desired to vary the degree of movement of the hammer member or the lever 22 which carries the hammer member, it is merely necessary that the operator move the lever 51 so that the pawl 52 thereof will be engaged within the desired one of the notches 53. This movement of the lever 51 85 results in movement of the link 50, lever 49 and link 47 and this will of course change the position of the block 37 within the bifurcation at the rear end of the lever so that the leverage exerted upon the lever will be varied. It is of course apparent that the degree of movement of the block 37 with respect to the lever 22 is controlled entirely by 90 the length of the slots 25 in the lever.

From the foregoing description and a 105 study of the drawings it will be apparent that I have thus provided a simply constructed and consequently inexpensive machine which will be very efficient and powerful in action as a power hammer, which is provided with novel and effectual cushioning means, which includes means whereby the device may be thrown into or out of gear at an instant's notice, and which is moreover provided with a very simple device whereby 110 the degree of movement of the hammer member may be varied to meet different conditions.

While I have shown and described the 115 preferred embodiment of the invention, it is of course to be understood that I reserve the right to make such changes in the form, construction and arrangement of parts as will not depart from the spirit of the invention or the scope of the subjoined claims. 120

Having thus described my invention I claim:

1. A device of the character described comprising a base, a pair of uprights rising therefrom, an anvil member on one of said uprights, a lever pivoted upon the other upright and having its forward end provided with a hammer cooperating with said anvil, the rear end of said lever being bifurcated and formed with longitudinal slots, a shaft journaled upon said base, means for rotating said shaft, a cam on said shaft, an eccentric strap encircling said cam, a rod connected with said strap, a block engaged upon said rod and having trunnions disposed through said slots, and means for moving said trunnions along said slots whereby to vary the leverage upon said lever. 35
2. A device of the character described comprising a base, a pair of uprights rising therefrom an anvil member on one of said uprights, a lever pivoted upon the other upright and having its forward end provided with a hammer cooperating with said anvil, the rear of said lever being bifurcated and formed with longitudinal slots, a shaft journaled upon said base, 40 means for rotating said shaft, a cam on said shaft, an eccentric strap encircling said cam a rod connected with said strap, a block engaged upon said rod and having trunnions disposed through said slots, and means for moving said trunnions along said slots whereby to vary the leverage upon said lever. 45
3. A device of this character described comprising a base, a pair of uprights rising therefrom, an anvil member on one of said uprights, a lever pivoted upon the other upright and having its forward end provided with a hammer cooperating with said anvil, the rear of said lever being bifurcated and formed with longitudinal slots, a shaft journaled upon said base, 50 means for rotating said shaft, a cam on said shaft, an eccentric strap encircling said cam a rod connected with said strap, a block engaged upon said rod and having trunnions disposed through said slots, and means for moving said trunnions along said slots whereby to vary the leverage upon said lever, said means comprising a lever pivoted upon the base, a second lever pivoted upon said second named upright and connected with said second named lever, and a link connected with the upper end of said last named lever and with one of said trunnions. 55
